UNITED STATES PATENT OFFICE

PETER RODYENKO, OF MANHASSET, NEW YORK

DESIGN FOR A HOLDER FOR A BEVERAGE SHAKER

Application filed December 21, 1931. Serial No. 42,164. Term of patent 3½ years.

To all whom it may concern:

Be it known that I, PETER RODYENKO, a citizen of the United States, residing in Manhasset, county of Nassau, State of New York, have invented a new, original, and ornamental Design for a Holder for a Beverage Shaker, of which the following is a specification, reference being had to the accompanying drawing, forming part thereof.

The drawing is a perspective view of the article showing my new design.

I claim:

The ornamental design for a holder for a beverage shaker, as shown.

PETER RODYENKO.
